US00D776153S

(12) **United States Design Patent** (10) **Patent No.:** **US D776,153 S**
Yampolskiy et al. (45) **Date of Patent:** **** Jan. 10, 2017**

(54) **DISPLAY SCREEN OR PORTION THEREOF WITH GRAPHICAL USER INTERFACE FOR SECURITY TO REDUCE RISK**

(71) Applicant: **Security Scorecard, Inc.**, New York City, NY (US)

(72) Inventors: **Aleksandr Yampolskiy**, New York, NY (US); **Samuel Kassoumeh**, Brooklyn, NY (US)

(73) Assignee: **Security Scorecard, Inc.**, New York City, NY (US)

(**) Term: **15 Years**

(21) Appl. No.: **29/550,886**

(22) Filed: **Jan. 7, 2016**

(57) **CLAIM**

The ornamental design for a display screen or portion thereof with graphical user interface for security to reduce risk, as shown and described.

DESCRIPTION

The FIGURE is a front view showing of our design. The broken line showing of the display screen and graphical user interface elements are included for the purpose of illustrating portions of the article and form no part of the claimed design.

1 Claim, 1 Drawing Sheet
